UNITED STATES PATENT OFFICE

2,567,771

WINDOW-OPENING GAUGE

Fraser A. Hurd, Liverpool, N. Y.

Application January 8, 1947, Serial No. 720,705

3 Claims.

(Cl. 33—194)

1

This invention has to do with a device for gauging the contour of a window or door opening, whereby a storm sash, screen, or door, may be cut to the proper dimension and contour for the opening.

The invention has as an object a window-opening gauge embodying a structure which is particularly simple and economical to manufacture and which can be conveniently manipulated by a workman working on a ladder.

The invention has as a further object a device of the type referred to comprising a plate, or body member, having a plurality of arms extending outwardly, and which are moved into engagement with the four corners of the opening, and auxiliary arms for engaging intermediate portions of the opening, all whereby the dimensions and exact contour of the opening are quickly and accurately reproduced on the sash, or screen, to be fitted therein.

The invention consists in the novel features and in the combinations and constructions hereinafter set forth and claimed.

In describing this invention, reference is had to the accompanying drawings in which like characters designate corresponding parts in all the views.

Figure 1 is a front-elevational view of a device embodying my invention, with the opening shown in dotted outline.

Figure 2 is a side elevational view of the device shown in Figure 1.

Figure 3 is a sectional view taken on line 3—3, Figure 1.

The device comprises a body or rectangular plate 10. This plate may be formed of light material, such as laminated plywood, and is provided with a plurality of arms 11 extending outwardly from the plate. The arms 11 are formed with rounded ends 12 or, if desired, the extending ends may be provided with rollers 13. The arms 11 are adjustable lengthwise and transversely of the plate 10 and accordingly of the window or door opening, illustrated in dotted outline at 15 in Figure 1, to move the ends of the arms into engagement with the corners of the opening. This adjustment is brought about in the structure disclosed by elongated slots 16 formed intermediate the ends of the arms 11. Clamping screws 17 extend through the slots 16 and also through slots 18 formed in the plate 10 and extending in angular relation to the sides and ends thereof.

The inner ends of the arms 11 are provided with clamping bolts 19 arranged in slots 20

formed in the central portion of the plate 10. The slots 20 extend in angular relation to the slots 16 and also to the ends and sides of the plate. The arrangement is such that the arms 11 may be adjusted outwardly from the corner portions of the plate 10, and the ends of the arms movable lengthwise and transversely of the window opening, whereby the ends of the arms are moved into engagement with the corners 10 of the opening and are then locked to the plate by the screws 17, 19.

Preferably the device is provided with an arm 22 arranged centrally of the plate and extending downwardly from the bottom edge thereof. This 15 arm is slidably mounted in a U-shaped bracket 24 secured to the under side of the plate, and is provided with a clamping screw 25 operable in an elongated slot 26 extending lengthwise of the plate 10. The purpose of the arm 22 is to support 20 the device when it is initially placed into the opening, and it also serves in gauging the contour of the lower edge of the opening. Auxiliary means 28 are mounted on each side of the plate 10 and are movable into engagement with the 25 sides of the opening. These arms are also adjustable on the plate, whereby the sides of the opening may be gauged substantially midway between the top and bottom edges, or at any point where the sides of the opening appear to bulge, or are 30 irregular. To accomplish this movement, the arms 28 are provided with slots 29, and the plate 10 is formed with slots 30. These slots accommodate a clamping bolt 31, and this arrangement permits the arms to be swung outwardly 35 into engagement with the sides of the opening and to be moved lengthwise thereof, as illustrated in Figure 1.

In use, the arms 11 are moved to retracted position, the device placed in the opening resting upon the arm 22 which may be previously adjusted to position the plate approximately in the center of the opening. Thereafter, the arms 11 are released and moved outwardly into engagement with each corner of the window opening. 45 In order to facilitate this movement, especially when the worker is positioned upon a ladder, the inner ends of the arms 11 are connected to tension springs 32. The ends of the springs 32 are connected to pulleys 33. A flexible strand 34 is trained over the pulleys 33 and stationary pulleys 35 mounted upon the plate adjacent the ends thereof, whereby the springs 32 yieldingly urge all of the arms 11 outwardly. Accordingly, it is only necessary to loosen the clamping bolts 50 17, 19, and the arms move outwardly moving the

ends of the arms into engagement with the corners of the opening, whereupon the arms may be securely clamped to the plate by the clamping screws. The auxiliary arms 28 are then moved outwardly into engagement with the sides of the opening and clamped by the screws 31. The device is then laid upon the sash, or door, and a straight edge is used to scribe the outline of the opening. When the sash, or door, is cut to this outline, it is a perfect fit for the opening. The plate may be provided with one or more handles 35 for convenient manipulation of the device.

I am not unmindful of the fact that many templates and gauging devices of the general type have been previously used. However, they have not been satisfactory due to their complicated structure and the fact that they do not gauge the corners of the opening. It will be apparent that my device is most convenient to manipulate and that it gives an accurate gauging of the contour of the opening. The device is simple to operate and, by its structure, will gauge all window openings due to the relatively extensive adjustment of the arms 11. By substituting longer arms, the same device is employed for gauging door openings.

What I claim is:

1. A window opening gauge comprising a rectangular plate, an arm extending substantially diagonally outwardly from each corner portion of the plate, the central portion of said plate being formed with a plurality of slots extending lengthwise of the plate and each corner portion of said plate being formed with a slot extending transversely across the corner portion of the plate and in angular relation to said first mentioned slots, each of said arms being formed with a slot arranged intermediate its ends and extending lengthwise thereof, a clamping member extending through the slot in each of said arms and through the complementary corner slot in said plate, a clamping member carried by the inner end of each of said arms and being slidably arranged in one of said lengthwise extending slots, spring means, flexible connections between said spring means and the inner ends of said arms, said spring means and connections being operable to yielding urge said arms collectively out-

wardly into engagement with the corners of the window opening, and said clamp members being operable to fixedly clamp the arms to the plate.

2. A window opening gauge comprising a rectangular plate, the central portion of said plate being formed with a plurality of slots extending substantially lengthwise of the plate, each corner portion of said plate being formed with a slot extending transversely across the corner portion of the plate and in angular relation to said first mentioned slots, an arm positioned to extend substantially diagonally outwardly from each corner portion of the plate, each of said arms being formed with a slot arranged intermediate its ends and extending lengthwise thereof, a clamping member extending through the slot in each of said arms and through the complementary corner slot in said plate, and a clamping member carried by the inner end of each of said arms and being slidably arranged in one of said lengthwise extending slots.

3. A window opening gauge comprising a rectangular plate, a guide member mounted on each corner portion of the plate and being movable transversely thereof, an arm extending from the central portion of the plate outwardly in a diagonal direction from each corner portion of the plate, the inner end of each of said arms being pivotally connected to a guide means movable substantially lengthwise of said plate, the intermediate portion of each arm being slidably connected to one of said first mentioned corner guide members, and each of said corner guide members having a clamping means cooperable to fixedly clamp the guide member and the associated arm to said plate.
